UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

AUTOMATIC LUBRICATOR

Application filed July 28, 1927. Serial No. 209,109.

My invention relates to automatic lubricators.

An object of the invention is to provide an improved automatic lubricator for fluid pressure lines adapted to function in a plurality of positions. Another object is to provide an improved lubricator for use in a mining machine adapted to operate in any cutting position of the machine. A still further object is to provide a plurality of filling openings for a lubricant reservoir so that the same may be filled whenever any part of the lubricator is inaccessible. Other objects and advantages will subsequently more fully appear.

In the accompanying drawings I have shown for purposes of illustration one form which my invention may assume in practice.

In these drawings,—

Fig. 1 illustrates a mining machine partly in elevation and partly in section having my improved lubricator associated therewith.

Fig. 2 shows a longitudinal vertical section through the lubricator.

Fig. 3 is a vertical section on the line 3—3 of Fig. 2.

Fig. 4 is an end elevational view of the mining machine shown in Fig. 1.

The mining machine illustrated in Figs. 1 and 4 may be of any well known type adapted for overcutting and undercutting. The particular machine illustrated has a feed section 1, a motor section 2, and a cutter bar carrying section 3 held together by suitable retaining means 4. The section 3 has a swinging cutter bar 5 pivotally mounted thereon and this cutter bar carries a cutter bit chain 6. As shown in Fig. 4 a suitable handle 7 for controlling the motor projects from the end of the feed section and another handle 8 is located on the opposite side of the machine for controlling the feeding mechanism (not shown). The feed section 1 has an internal compartment 9 through which leads a line 10 for conveying motive fluid to the motor section from a supply line 11. A control valve 13 is connected in this line adjacent the end of the feed section and operated by the handle 7 through a suitable mechanical connection (not illustrated). My improved lubricator which is generally des-

ignated 14 is disposed in the compartment 9 and connected in the fluid supply line 10. As better illustrated in Figs. 2 and 3, the lubricator comprises a lubricant reservoir 15, fluid passages 16 and 17 for conducting the motive fluid around the reservoir, and internally threaded portions 18 and 19 for connection to the supply line. The lubricant reservoir has threaded internal openings 20 and 21 in communication with the fluid conveying passages 16 and 17 respectively, for receiving vent plugs 22. Each of these vent plugs has an opening 23 of restricted size for a purpose to be later set forth. The outer walls of the fluid conducting passages 16 and 17 have threaded openings 24 disposed in alinement with the vent plugs, and in each of these openings a removable plug 25 is placed in order that the vent plugs may be accessible for cleaning purposes.

I have provided a plurality of means for introducing lubricant into the reservoir 15 so that at least one filling connection is accessible in any position of the lubricator. As shown in Fig. 3 a pipe 26 is threaded into the walls of the reservoir and connected to this pipe is a vertically disposed member 27 having removable plugs 28 and 29 threaded into its opposite ends. It will therefore be apparent that when the member 27 is accessible one of the plugs 28 or 29 may be removed for filling the reservoir with lubricant. I have also provided a filling connection at the top of the lubricator opening into the lubricant reservoir at 30 and this opening is adapted to be closed by a removable plug 31. A similar filling opening 32 and removable plug 33 are located on the bottom side of the lubricator so that when the plug 31 is inaccessible the plug 33 may be removed for filling the reservoir. The mining machine casing has threaded openings 34 disposed in alinement with the filler plugs 31 and 33 and these openings are closed by removable plugs 35 so that the lubricant reservoir may be filled through the mining machine casing in the event that the member 27 is inaccessible.

In operation, assuming the lubricator to be in the position shown in Figs. 2 and 3, pressure fluid will flow from the connection 100

19 through the passages 16 and 17 to the connection 18 at the opposite side of the lubricator. The upper opening 23 will serve to equalize the pressure between the lubricant reservoir and the fluid conducting passages and lubricant will flow through the lower opening 23 into the fluid conducting passage 17, where it is picked up by the current of motive fluid and carried into the line 10, thus continuously supplying lubricant to the motor along with the motive fluid. If the lubricator is now inverted, as when the mining machine is turned from the overcutting position shown in Fig. 1 to the undercutting position, the vent opening which formerly served as an outlet for lubricant will now operate as an equalizing passage, and the vent opening which is in the lower position will operate as the lubricant outlet, thus supplying lubricant to the motor in the same manner as in the other position. The manner of filling the lubricant reservoir will be obvious from the above description of the filling connections and filler plugs.

25 It will of course be understood that my lubricator is not limited to the shape shown or to use in a mining machine, but may be used in connection with any fluid pressure motor such as commonly employed in rock drills, 30 being thus made much wider and lower to cause it to rest firmly in one of its more effective positions. The advantage of the plurality of vent openings in the reservoir at different levels when the lubricator is connected in a flexible line will be obvious since 35 the lubricator is very apt to be accidentally turned over into any position.

While I have in this application specifically described one form which my invention 40 may assume in practice, it will be understood that this form of the same is used for purposes of illustration and that the invention may be modified and embodied in various other forms without departing from its spirit 45 or the scope of the appended claims.

What I claim as new and desire to secure by Letters Patent is:

1. An automatic lubricator for fluid pressure motors comprising a casing adapted to be connected in the fluid pressure line, a lubricant reservoir in said casing having a plurality of openings therein at different levels, and means for subjecting each of said openings to fluid pressure in said casing whereby 55 the upper one of said openings in any of a plurality of positions of the lubricator is adapted to serve as an inlet for pressure fluid from said casing while lubricant flows by gravity through the other of said openings.

2. In a mining machine, an enclosed casing having a compartment therein, a fluid pressure line leading through said compartment, and an automatic lubricator connected in said line and disposed in said compartment, said lubricator comprising a lubricant 60

reservoir having a plurality of openings therein at different levels, means for conducting pressure fluid through said lubricator, said conducting means communicating with said openings whereby the one of said openings above the level of lubricant in said reservoir in any of a plurality of positions of the lubricator constitutes an inlet for pressure fluid while lubricant flows by gravity through the other of said openings.

3. In a lubricating system, a casing having therein an automatic lubricator for a fluid pressure motor, said lubricator comprising a lubricant reservoir having a plurality of restricted openings therein at different levels, means for conducting motive fluid around said reservoir to said motor comprising passages above and below the reservoir each communicating with one of said openings, and selectively removable means for closing a plurality of filling openings at different levels in said reservoir, and removable plugs in said casing in alignment with said filling openings to permit access to said removable closing means.

4. An automatic lubricator for a fluid pressure line comprising a lubricant reservoir, a plurality of passages communicating with said fluid pressure line and opening into said reservoir at different levels, either of said passages adapted to supply lubricant by gravity into said fluid pressure line when said reservoir is in such position that it is below the level of lubricant and to conduct pressure fluid into said reservoir when it is above said level, and filling openings communicating with said reservoir at different levels.

5. In a mining machine, an enclosed casing having a compartment therein, a fluid pressure line leading through said compartment, and an automatic lubricator connected in said line and disposed in said compartment, said lubricator comprising a lubricant reservoir, a plurality of passages communicating with said fluid pressure line and opening into said reservoir at different levels, either of said passages adapted to supply lubricant by gravity into said fluid pressure line when said reservoir is in such a position that it is below the level of lubricant or to conduct pressure fluid into said reservoir when it is above said level, and selectively removable means permitting filling said lubricant reservoir through opposite sides of said mining machine casing.

6. In a mining machine, an enclosed casing having a compartment therein, a fluid pressure line leading through said compartment, and an automatic lubricator connected in said line and disposed in said compartment, said lubricator comprising a lubricant reservoir having a plurality of restricted openings therein at different levels, means for conducting motive fluid around said reservoir to said motor comprising passages above

and below the reservoir, each communicating with one of said openings, means for filling said lubricant reservoir comprising passages extending through said fluid conducting passages and closed by removable plugs so that at least one may be accessible in any position of the machine, said mining machine casing having an opening therein disposed in alignment with each of said plugs, and removable

5 plugs for each of said latter openings.

10 7. An automatic lubricator for pressure fluid motors comprising a casing adapted to be connected in the pressure fluid line and having means forming therein a lubricant reservoir, said reservoir forming means having spaced openings therein, said casing being disposable during use of said lubricator in a substantially horizontal position in which one of said openings is at a higher

15 level than the other and also in a different substantially horizontal position in which the last mentioned one of said openings is at a higher level than the first, and said casing having means extending therethrough for

20 conducting pressure fluid to be supplied with lubricant and with which said openings communicate, whereby in either of said casing positions the upper one of said openings is adapted to serve as an inlet for pressure fluid

25

30 while lubricant flows by gravity through the other of said openings.

In testimony whereof I affix my signature.
MORRIS P. HOLMES.
